CLAIM

I claim the ornamental design for the anti-theft device, as shown and described.

DESCRIPTION

FIG. 1 is a front perspective view of the vehicle anti-theft device embodying by design;

FIG. 2 is the anti-theft device in use in the vehicle;

FIG. 3 is a front view of the anti-theft device;

FIG. 4 is a back view of the anti-theft device;

FIG. 5 is a left side elevation of the anti-theft device;

FIG. 6 is a right side elevation of the anti-theft device;

FIG. 7 is a top view of the anti-theft device; and,

FIG. 8 is a bottom view of the anti-theft device.

The broken lines are shown for illustrative purposes only and form no part of the claimed design.
